UNITED STATES PATENT OFFICE.

NORMAN LIPSKY, OF NEW YORK, N. Y., ASSIGNOR TO HALCOLITE COMPANY, INC., OF NEW YORK, N. Y., A CORPORATION OF NEW YORK.

DESIGN FOR A LIGHTING-FIXTURE CANOPY OR ANALOGOUS ARTICLE.

Application filed November 5, 1927. Serial No. 24,016. Term of patent 7 years.

To all whom it may concern:

Be it known that I, NORMAN LIPSKY, a citizen of the United States of America, and a resident of the city, county, and State of New York, have invented a new, original, and ornamental Design for a Lighting-Fixture Canopy or Analogous Article, of which the following is a specification, reference being had to the accompanying drawing, forming a part hereof.

The single figure in the drawing shows a perspective view of the lighting fixture can-

opy or analogous article. A fragment of the surface ornamentation of the lighting fixture canopy or analogous article is illustrated in the right hand portion of the figure, it being understood that the remainder of the surface of the lighting fixture canopy or analogous article is similarly treated.

I claim:

The ornamental design for a lighting fixture canopy or analogous article substantially as shown and described.

NORMAN LIPSKY.
